GARMENT

Morris Michel, Chicago, Ill.

Application July 26, 1934, Serial No. 737,082

2 Claims. (Cl. 2—85)

This invention relates to a garment, and more particularly to a novel and improved means for finishing off the front ends thereof to prevent the same from turning out when worn.

Those familiar with this art know how difficult it is to construct a garment such, for example, as a lady's coat or the like, so that the outer free edges thereof will hang freely and will not turn out particularly at the bottom portion thereof when the garment is being worn. Several attempts have been made to overcome the above difficulty, but so far none of these have been entirely successful. It is, therefore, the main object of this invention to construct a garment of the character described and to so finish off the free outer edges thereof as to entirely eliminate the possibility of said outer edges turning or folding out, said object being accomplished by securing the infolded edge portion of the garment to a longitudinal edge of a taping strip, the opposed longitudinal edge of said taping strip being secured to the body of the garment, the latter edge of said strip being secured inwardly of the first mentioned edge.

Another object of this invention is to provide a finished edge for a garment which consists in folding the body of the material upon itself to produce an infolded edge portion and securing said infolded edge portion to the body portion by means of a taping strip, one longitudinal edge of which strip is secured to the under face of said infolded edge portion and the opposed longitudinal edge is secured to the body portion, the securing means for said taping strip may be spaced from each other and arranged so as to permit the said infolded edge portion to move inwardly, but to prevent the same from moving outwardly.

A further object of this invention is to provide a novel and improved means for finishing off the free edge of a garment which will be simple in construction, which may be done economically and conveniently, and which will be highly efficient for carrying out the purposes for which it is designed.

With the foregoing and other objects in view, which will appear as the description proceeds, the invention consists in certain novel features of construction, arrangement and combination of parts, hereinafter more fully described, illustrated in the accompanying drawing and particularly pointed out in the appended claims, it being understood that various changes in the form, proportion, size and minor details of the structure or

sacrificing any of the advantages of the invention.

For the purpose of facilitating an understanding of my invention, I have illustrated in the accompanying drawing a preferred embodiment thereof, from an inspection of which when considered in connection with the following description, my invention, its mode of construction, assembly and operation, and many of its advantages should be readily understood and appreciated.

Referring to the drawing in which the same characters of reference are employed to indicate corresponding or similar parts throughout the several figures of the drawing:

Figure 1 is a view in perspective of a woman's garment constructed in accordance with the principles of this invention;

Fig. 2 is a plan view of a fragmentary portion of the inside of the garment constructed in accordance with my invention;

Fig. 3 is a view in perspective of a fragmentary portion of the garment, portions thereof being opened up for the purpose of illustrating the same more fully; and

Fig. 4 is a sectional view taken on line 4—4 of Fig. 2.

Referring to the drawing more specifically by characters of reference, the numeral 10 designates the body of a garment, the free edge 11 of which is folded back upon itself to form an infolded edge portion 12. A row of stitching 13 may be provided immediately adjacent the free folded edge 12 to give to the same a finished appearance. In order to prevent the portion 12 from folding outwardly when the garment is being worn, I have provided the following novel means for securing the portion 12 to the body portion 10.

In the embodiment illustrated, said means consists of a taping strip 14 which is disposed between the portion 12 and body portion 10, said taping strip being of substantial width, which, in practice, may be approximately from an inch to an inch and a half, and has one longitudinal edge thereof secured by a row of stitching 15 to the under face of the infolded edge portion 12. The opposed longitudinal edge of said strip 14 is secured by means of a row of stitching 16 to the inner face of the body portion 10, said row of stitching 16 being disposed inwardly of said first mentioned row of stitching 15, as shown more clearly in Fig. 4 of the drawing. By reason of this arrangement, it will be readily apparent that the infolded edge portion 12 will readily give or move to the right as viewed in Fig. 4, but will be

prevented by means of the taping strip 14 from moving or giving to the left, as viewed in said Fig. 4.

In actual practice, the taping strip 14 will 5 extend to a point 17 which is spaced from the bottom edge 18 of the garment, as shown in Fig. 2, and that portion of the infolded edge 12 which is disposed between the point 17 and bottom edge 18 is fastened to the body of the garment by 10 means of a small thread chain 19, one end of which is secured to the infolded edge portion 12, as shown at 20, and the other edge of which is secured to the body portion of the garment as 15 shown at 21.

From the above it should be readily apparent 15 that when a garment is constructed in the manner hereinbefore described, the front edge thereof will be prevented at all times from turning or 20 folding outwardly by reason of the fact that the infolded edge portion 12 will be held against 25 movement in an outwardly direction by means of the taping strip 14. This strip, however, will permit said infolded edge portion 12 to move inwardly a distance equal substantially to the 30 width of the strip 14 between the two rows of 35 stitches 15 and 16.

I believe that my invention, its mode of construction and assembly, and many of its advantages should be readily understood from the foregoing without further description, and it should also be manifest that while a preferred embodiment 30 of the invention has been shown and described for illustrative purposes, the structural details are nevertheless capable of wide variation 35 within the purview of my invention as defined in the appended claims.

What I claim and desire to secure by Letters Patent of the United States is:

1. In a garment of the character described, 40 means for finishing off the free longitudinal edges thereof, said means including an infolded edge portion, a row of stitching provided immediately adjacent the folded edge, said stitching extending to a point spaced from the lower edge of the gar-

ment whereby said lowermost edge of said infolded portion will remain unsecured to the body of the garment, and a taping strip disposed between said infolded edge portion and body portion, said taping strip having one longitudinal edge thereof secured by a row of stitching to the infolded edge portion only, and the opposed longitudinal edge thereof secured by a row of stitching to the body portion only, said strip being of considerable width with the rows of stitching provided therethrough being spaced from each other with the first mentioned row being disposed inwardly of said second mentioned row, whereby said infolded edge portion may move inwardly relative to said body portion but will be held 15 against movement outwardly relative to said body portion by said taping strip.

2. In a garment of the character described, means for finishing off the free longitudinal edges thereof, said means including an infolded edge portion, a row of stitching provided immediately adjacent the folded edge, said stitching extending to a point spaced from the lower edge of the garment whereby said lowermost edge of said infolded portion will remain unsecured to the body of the garment, and a taping strip disposed between said infolded edge portion and body portion, said taping strip having one longitudinal edge thereof secured by a row of stitching to the infolded edge portion only, and the opposed longitudinal edge thereof secured by a row of stitching to the body portion only, said strip being of considerable width with the rows of stitching provided therethrough being spaced from each other with the first mentioned row being disposed inwardly of said second mentioned row, whereby said infolded edge portion may move inwardly relative to said body portion but will be held against movement outwardly relative to said body portion by said taping strip, and a 40 flexible connection between the lowermost unsecured corner of the infolded edge portion and the body.

MORRIS MICHEL.
